FEED MECHANISM FOR SEWING MACHINES

Harold J. Le Vesconte, Western Springs, and
 Clarence C. Smith, Chicago, Ill., assignors to
 Union Special Machine Company, Chicago,
 Ill., a corporation of Illinois

Application January 30, 1936, Serial No. 61,472

20 Claims. (Cl. 112—215)

This invention relates to feed mechanisms for sewing machines and the like, and particularly to what are known as four motion feeds especially adapted for lock stitch sewing machines wherein 5 a rotary hook cooperates with the needle or needles in the formation of the stitches.

More specifically, the present invention has reference to sewing machine feed mechanisms of a type featured in a copending application Serial 10 No. 51,992, filed jointly by Norman V. Christensen, Clarence C. Smith and George Sauer on November 29, 1935, which is characterized by having a single rotary actuator from whence both the feed and lift movements of the feed dog are obtained 15 through the aid of interposed motion translating instrumentalities.

Our invention is directed toward refinements in feed mechanism of the kind specifically referred to which favor greater structural simplicity with 20 attendant minimization of friction and momentum and attainment of a corresponding decrease in wear and vibration of the parts so that the sewing machine in which the mechanism is incorporated can be safely operated at higher speeds 25 than heretofore possible; and which moreover favor greater compactness, with the parts so grouped in respect to the rotary hook so that the latter is left entirely unobstructed at the front of the sewing machine for convenience of ready access 30 in removing and replacing the bobbins.

In connection with a feed mechanism having the above attributes, it is a further aim of our invention to provide for regulation of the stroke and the direction of feed without attendant change 35 in the vertical or lift movements of the feed dog.

The foregoing, as well as other objects and attendant advantages, are all inherent in the mechanism hereinafter described in detail and shown in the attached drawings, wherein Fig. I is 40 a fragmentary plan sectional view of a lock stitch sewing machine generally of the type featured in another pending application Serial No. 670,186 filed by Norman V. Christensen and Charles F. Rubel on May 9, 1933, and conveniently embodying our improved feed mechanism.

Fig. II is a fragmentary perspective view of the feed mechanism.

Fig. III is a fragmentary longitudinal sectional view taken as indicated by the arrows III—III in 50 Fig. I.

Fig. IV is a transverse sectional view taken as indicated by the arrows IV—IV in Fig. I.

Figs. V, VI, VII and VIII are detail sectional views corresponding to Fig. IV and showing the 55 parts of the feed mechanism in different positions.

The horizontal bed plate or work support of the partly illustrated sewing machine is designated 1, and as shown, has an integrally-formed pendant projection 2 whereof the portion 3 is made hollow to serve as a gear housing and is closed at the bottom by a removable plate 4. Journaled in a bearing bushing 5 (Fig. I) set into the pendant projection 2 of the work support 1 is a shaft 6 to the forward end of which is secured a rotary hook 7 of a suitable type capable of cooperating with the needle (not shown) of the machine to form lock stitches in the usual way. The hook shaft 6 is held against axial displacement jointly by a collar 8 affixed thereto at the left hand end and abutting the outer end of the bushing 5, and by a gear pinion 9 thereon engaging the inner end of said bushing within the gear housing 3. As shown in Fig. I, the pinion 9 meshes with a gear wheel 10 fast on a rotary shaft 11 which extends through the gear housing 3 and which is journaled in bearing bushings 12 and 13 set respectively into the front and rear walls of said gear housing, the bushing 12 being secured by screws 14. The shaft 11 may be driven for example, in the manner disclosed in the copending application 670,186 hereinbefore referred to; and through the gears 9 and 10 rotary motion is imparted from said shaft to the hook shaft 6 at increased speed, said gears having in the present instance a one to two ratio. The bushing 12 is lubricated by oil introduced 30 from above through a vertical oil hole 15 in the work support 1; (Fig. III) while the gears 9 and 10 and the bearing 13 are lubricated by oil splashed within the housing 3 which is normally kept filled to the level indicated in Fig. III.

The feed mechanism with which the present invention is more especially concerned, comprises a feed dog 16 which operates above the rotary hook 7, as shown in Fig. IV, and which is adjustably secured to the forward end of a feed dog carrier or bar 17 by means of a screw 18. It is to be particularly noted from Figs. I, III and IV that the parts for actuating the feed dog 16 are all disposed at the side of the rotary hook 7 rearward of the direction of feed so that said hook is left unobstructed at the front of the machine for convenience of ready access in removing and replacing bobbins.

Fixed in a boss 19 at the rear end of the feed bar 17 is a transverse wrist pin 20 whereof the opposite ends are engaged in aligned bosses 21 and 22 of a rocker 23. The fulcrum shaft 24 of the rocker 23 has its opposite ends journaled in bushings 25 and 26 set into spaced pendant lugs 27 and 28 of the work support 1. The rocker 55

23 receives its movement from a rotary actuator in the form of a small crank pin 29 on a head 30 at the end of the shaft 11, through a horizontal pitman 31 comprising two telescoping components 32 and 33. The component 32 of the pitman 31 has a sleeve portion 34 which is intercepted by a yoke 35, and an end boss 36 in which is secured a transverse wrist pin 37 whereof the opposite ends are respectively engaged in another 10 pair of spaced pivot bosses 38 and 39 of the rocker 23. At 40, the component 32 of the pitman 31 has pivotal connection with one end of a link 41 whereof the opposite end is in turn pivotally connected at 42 to the outer end of an 15 arm 43 affixed to a regulating shaft 44 which is journaled in the pendant projection 3 of the work support 1. By the elements thus far described, horizontal feed movements are imparted from the shaft 11 to the feed dog 16 to progressively 20 advance the fabric in the machine in the direction of the arrow shown in Fig. IV, the stroke of said dog being adjustable or its action reversed through partial turning of the regulating shaft 44 in the manner fully set forth in Patent No. 25 2,035,508, granted on March 31, 1936, to George Sauer and Clarence C. Smith.

The means whereby the necessary vertical or lift movements are imparted in the feed dog 16 include a short oscillating shaft 45 which is axially aligned substantially with the shaft 11 and which is journaled in an inset bushing 46 of a bearing block 47 secured by a pair of screws 48 to the bottom of the work support 1 of the machine. At its outer or left hand end the oscillating shaft 45 has a diametrically-reduced eccentric portion or crank 49 to which is in turn adjustably secured, by means of a screw 50, an eccentric 51. Embracing this eccentric 51 is a strap 52 having a pendant vertical link arm 53, 30 whereof the lower end is pivotally connected at 54 to a downwardly and forwardly curved under-reaching arm 55 of the feed bar 17. Integrally formed with, or secured to the right hand end of the rock shaft 45 is a downward arm 56 which 35 is coupled by means of a horizontal link 57 with a downward projection 58 on a split collar 59, which, by means of a screw 60, is clamped, with capacity for adjustment, to the shank 61 of the pitman component 33 within the opening of the 40 yoke portion 35 of the other pitman component 32.

The oscillating shaft 45 is lubricated by oil led thereto by way of a downward duct 62 from a small reservoir 63 in the top of the bearing block 55 47, said reservoir being accessible for filling through a hole 64 in the work support 1, see Figs. I and III. Extending laterally outward from the reservoir 63 is a tube 65 which overreaches the head 66 of the pitman component 33, said head 60 having a boss 67 at the top with an elongated recess 68 and a communicating oil hole 69 (Figs. I and III) leading down to the crank pin 29. During each rotation of the crank 29, the boss 67 on the head 66 of the pitman component 33 wipes 65 against an oil conducting wick 70, (Fig. III) protruding from the downwardly beveled end of the tube 65 and leading from the reservoir 63 in the bearing block 47. In this way, adequate oil is 70 supplied from the reservoir 63 to the crank 29 to keep the latter thoroughly lubricated at all times.

Considering the shaft 11 to be rotating clockwise as indicated by the arrows in Figs. V and VII, the operation of the feed mechanism, in- 75

sofar as the lift movements of the feed dog 16 are concerned, is as follows:

In Figs. IV and VI, the feed dog is elevated and positioned midway of its active or feed stroke to the left, with the crank 29 of the rotary shaft 11 positioned as shown in Fig. V, and the crank 49 and the attached eccentric 51 of the oscillating shaft 45 positioned as shown in Fig. VI. Movement of the crank 29 from the position of Fig. V to that of Fig. VII is attended by bodily depression of the pitman 31 as well as by incidental leftward movement of the pitman component 33 and the feed dog 16 as indicated by the arrow on the latter in Fig. VI. As a consequence of the leftward movement of the pitman component 33, the oscillating shaft 45 is swung clockwise from the position of Fig. V to the position of Fig. VII, whereby, through the crank 49, the attached eccentric 51 and the strap link 53, the feed dog 16 is lowered to the position of Fig. VIII 20 with its teeth below the top of the work support 1. During rotation of the shaft 11 through another quadrant from the position of Fig. VII, the pitman 31 is bodily elevated while the component 33 continues leftward, with incidental further 25 clockwise movement of the oscillating shaft 45 so that the feed dog 16 is fully lowered by the time it reaches the midposition of its rightward or idling return stroke. During the remaining half rotation of the shaft 11 to complete the feed 30 cycle, reversal of the foregoing takes place, that is to say, the oscillating shaft 45 and the eccentric 51 thereon are swung anticlockwise with resultant elevation of the feed dog 16 through the medium of the strap link 53 and advance of said 35 feed dog to the position of Fig. VI on its leftward or active stroke. Thus, through the pitman 31, the link 57, the arm 56, the oscillating shaft 45, the eccentric 51 and the strap link 53, the horizontal component of movement of the 40 crank 29 on the rotary shaft 11 is translated into up and down or lift movements of the feed dog 16.

Since the link 57 is connected, through the split collar 59, to the pitman component 33 direct-connected to the crank 29 on the rotary 45 shaft 11, the lift movements of the feed dog will not be affected when adjustments are made in the feed stroke or the action of said dog reversed by means of the regulating shaft 44. A further advantage of our improved feed mechanism is that the timing of the lift movements of the dog 16 may be changed in respect to the feed movements thereof by adjusting the clamp collar 59 along the shank 61 of the pitman component 33; and if a change should be desired or required in 55 the lift movement, this may be effected simply by rotatively adjusting the eccentric 51 about the crank 49 on the oscillating shaft 45.

From the foregoing it will be realized that our improved feed mechanism is simple and compact with its parts so interconnected as to insure operation at high speeds, and so arranged as to leave the rotary hook conveniently accessible for bobbin changing.

We do not of course consider ourselves limited 65 to the precise details of construction and arrangement herein shown and described by way of example, since these can be considerably varied without departing from the spirit of our invention as defined in the appended claims. 70

Having thus described our invention, we claim:

1. Feed mechanism for sewing machines and the like comprising a feed dog and a carrier therefor; and means for imparting feed and lift movements to the feed dog, including a rocker, 75

5 a rotary actuator, a pitman connecting the rocker with the rotary actuator, an oscillating shaft, a link connecting an arm on said shaft with the pitman, and a link connecting a crank on said shaft with an underreaching arm on the feed dog carrier.

10 2. Feed mechanism for sewing machines and the like comprising a feed dog and a carrier therefor; and means for imparting feed and lift movements to the feed dog including a rocker, a rotating actuator, a pitman connecting the rocker with the rotary actuator, an oscillating shaft, a link connecting an arm on the shaft with the pitman, an eccentric rotatably adjustable about a crank on said shaft, and a strap link connecting the eccentric with the feed dog carrier.

15 3. Feed mechanism for sewing machines and the like comprising a feed dog and a carrier therefor; and means for imparting feed and lift movements to the feed dog including a rocker, a rotary shaft, a pitman connecting the rocker with a crank on said rotary shaft, an oscillating shaft substantially aligned axially with the rotating shaft; a horizontal link connecting an arm on said oscillating shaft with the pitman, and a vertical link connecting a crank on said oscillating shaft with an underreaching arm of the feed dog carrier.

20 4. Feed mechanism for sewing machines and the like comprising a feed dog and a carrier therefor; and means for imparting feed and lift movements to the feed dog including a rocker, a rotary shaft, a pitman connecting the rocker with a crank on said rotary shaft, an oscillating shaft substantially aligned axially with the rotating shaft, a link connecting an arm on said oscillating shaft with the pitman, an eccentric rotatably adjustable about a crank on the oscillating shaft, and a vertical strap link connecting the eccentric with the feed dog carrier.

25 5. Feed mechanism for sewing machines and the like comprising a feed dog and a carrier therefor; and means for imparting feed and lift movements to the feed dog including a rocker, a rotary actuator, a pitman with telescoping components connecting the rocker with the rotary actuator, a regulating shaft for adjusting the feed stroke of the dog, a link connecting an arm on said regulating shaft with that component of the pitman directly connected to the rocker, an oscillating shaft, a link connecting an arm on said oscillating shaft with that component of the pitman directly connected to the rotary actuator, and a link connecting a crank on the oscillating shaft with an underreaching arm of the feed dog carrier.

30 6. Feed mechanism for sewing machines and the like comprising a feed dog and a carrier therefor; and means for imparting feed and lift movements to the feed dog including a rocker, a rotary actuator, a pitman with telescoping components connecting the rocker with the rotary actuator, a regulating shaft for adjusting the feed stroke of the dog, a link connecting an arm on said regulating shaft with that component of the pitman directly connected to the rocker, an oscillating shaft, a link connecting an arm on the oscillating shaft with that component of the pitman directly connected to the rotary actuator, an eccentric rotatably adjustable about a crank on the oscillating shaft, and a strap link connecting the eccentric with the feed dog carrier.

35 7. Feed mechanism for sewing machines and

the like comprising a feed dog and a carrier therefor; and means for imparting feed and lift movements to the feed dog including a rocker, a rotary shaft, a pitman with telescoping components connecting the rocker with a crank on the rotary shaft, a regulating shaft for adjusting the feed stroke of the dog, a link connecting an arm on said regulating shaft with that component of the pitman directly connected to the rocker, an oscillating shaft in substantial alignment axially with the rotary shaft, a link connecting an arm on said oscillating shaft with that component of the pitman directly connected to the rotary actuator, and a link connecting a crank on the oscillating shaft with an underreaching arm of the feed dog carrier.

40 8. Feed mechanism for sewing machines and the like comprising a feed dog and a carrier therefor; and means for imparting feed and lift movements to the feed dog including a rocker, a rotary actuator, a pitman with telescoping components connecting the rocker with the rotary actuator, a regulating shaft for adjusting the feed stroke of the dog, a link connecting an arm on said regulating shaft with that component of the pitman directly connected to the rocker, an oscillating shaft, a horizontal link with one end thereof connected to an arm on said oscillating shaft and with the other end thereof connected with capacity for adjustment, to that component of the pitman directly connected to the rotary actuator, and a link connecting a crank on the oscillating shaft with an underreaching arm of the feed dog carrier.

45 9. Feed mechanism for sewing machines and the like comprising a feed dog and a carrier therefor; and means for imparting feed and lift movements to the feed dog including a rocker, a rotary actuator, a pitman with telescoping components connecting the rocker with the rotary actuator, a regulating shaft for adjusting the feed stroke of the dog, a link connecting an arm on said regulating shaft with that component of the pitman directly connected to the rocker, an oscillating shaft, a link with one end thereof connected to an arm on said oscillating shaft and the other end thereof connected with capacity for adjustment to that component of the pitman directly engaging the rotary actuator, an eccentric rotatably adjustable about a crank on the oscillating shaft, and a strap link connecting the eccentric with an underreaching arm of the feed dog carrier.

50 10. Feed mechanism for rotary hook sewing machines comprising a feed dog operating above the rotary hook, a carrier for said dog disposed wholly at one side of said rotary hook, a rotary shaft, and a single actuating member on said shaft from which the feed dog carrier receives a four-motion feeding movement.

55 11. Feed mechanism for rotary hook sewing machines comprising a feed dog operating above the rotary hook, a carrier for the feed dog disposed wholly at one side of said hook, a rotary shaft, a single actuating member on said shaft from which rising and falling movements, as well as back and forth movements are imparted to said carrier, and means whereby the length or direction of the feeding movements of said dog may be varied.

60 12. Feed mechanism for rotary hook sewing machines comprising a feed dog operating above the rotary hook, a carrier for the feed dog disposed wholly at one side of said hook, a rotary shaft, a single actuating member on said shaft

70

75

- from which rising and falling movements as well as back and forth movements are imparted to said carrier, and means whereby the length of the feed stroke of the dog may be varied and whereby the feeding action of said dog may be reversed without affection of its rising and falling movements.
13. Feed mechanism for rotary hook sewing machines comprising a feed dog; and means for imparting feed and lift movements to the feed dog disposed entirely to one side of the rotary hook, said means including a rocker, a rotary actuator, a carrier for the feed dog pivotally connected to the rocker, a horizontal pitman connecting the rocker with the rotary actuator, an oscillating shaft, a horizontal link connecting an arm on said oscillating shaft with the pitman aforesaid, and a vertical link connecting a crank on the oscillating shaft with an underreaching arm on the feed dog carrier.
14. Feed mechanism for rotary hook sewing machines comprising a feed dog; and means for imparting feed and lift movements to the feed dog disposed entirely to one side of the rotary hook, said means including a rocker, a rotary actuator, a carrier for the feed dog pivotally connected to the rocker, a horizontal pitman connecting the rocker with the rotary actuator, an oscillating shaft, a horizontal link connecting an arm on said oscillating shaft with the pitman, an eccentric rotatably adjustable about a crank pin on said oscillating shaft, and a vertical strap link connecting said eccentric with an underreaching arm on the feed dog carrier.
15. Feed mechanism for rotary hook sewing machines comprising a feed dog; and means for imparting feed and lift movements to the feed dog disposed entirely to one side of the rotary hook, said means including a rocker, a rotary shaft extending parallel with the shaft of the rotary hook, a carrier for the feed dog pivotally connected to the rocker, a horizontal pitman connecting the rocker with a crank on said rotary shaft, an oscillating shaft substantially aligned axially with the rotary shaft, a horizontal link connecting an arm on said oscillating shaft with the pitman, and a vertical link connecting a crank on the oscillating shaft with an underreaching arm on the feed dog carrier.
16. Feed mechanism for rotary hook sewing machines comprising a feed dog; and means for imparting feed and lift movements to the feed dog disposed entirely to one side of the rotary hook, said means including a rocker, a rotary actuator, a carrier for the feed dog pivotally connected to the rocker, a horizontal pitman with telescoping components connecting the rocker with the rotary actuator, a regulating shaft for adjusting the feed stroke of the dog; a link connecting an arm on the regulating shaft with that component of the pitman directly connected to the rocker, an oscillating shaft, a horizontal link connecting an arm on said oscillating shaft with that component of the pitman directly connected to the rotary actuator, a crank on the oscillating shaft, and a vertical link connecting said crank with an underreaching arm on the feed dog carrier.

17. Feed mechanism for rotary hook sewing machines comprising a feed dog; and means for imparting feed and lift movements to the feed dog disposed entirely to one side of the rotary hook, said means including a rocker, a rotary actuator, a carrier for the feed dog pivotally connected to the rocker, a horizontal pitman with telescoping components connecting the rocker with the rotary actuator, a regulating shaft for adjusting the feed stroke of the dog, a link connecting an arm on said regulating shaft with that component of the pitman directly connected to the rocker, an oscillating shaft; a horizontal link connecting an arm on said oscillating shaft with that component of the pitman directly connected to the rotary actuator, a crank on the oscillating shaft, an eccentric rotatably adjustable on the crank, and a vertical strap link connecting said eccentric with an underreaching arm on the feed dog carrier.
18. Feed mechanism for rotary hook sewing machines comprising a feed dog; and means for imparting feed and lift movements to the feed dog disposed entirely to one side of the rotary hook, said means including a rocker, a rotary shaft parallel with the shaft of the rotary hook, a carrier for the feed dog pivotally connected to the rocker, a horizontal pitman with telescoping components connecting the rocker with a crank on the rotary shaft, a regulating shaft for adjusting the feed stroke of the dog, a link connecting an arm on the regulating shaft with that component of the pitman directly connected with the rocker, an oscillating shaft substantially aligned axially with the rotary shaft, a horizontal link connecting an arm on said oscillating shaft with that component of the pitman directly connected to the crank, and a vertical link connecting a crank on the oscillating shaft with an underreaching arm on the feed dog carrier.

19. Feeding mechanism for sewing machines comprising a feed dog; means for imparting four-motion movements thereto including a rotary shaft, an oscillating member rearward of the point of stitch formation in the direction of feeding and operatively connected to the rotary shaft from which the dog receives its horizontal back and forth movements, and a second oscillating member operatively connected with the shaft and substantially axially aligned therewith from which the dog receives its rising and falling movements.

20. Feeding mechanism for sewing machines comprising a feed dog; means for imparting four-motion feed movements including a rotary shaft, an oscillating member rearward of the point of stitch formation in the direction of feeding from which the feed dog receives its horizontal back and forth movements, a second oscillating member substantially axially aligned with the rotary shaft from which the dog receives its rising and falling movements, and a single actuator on said shaft to which said oscillating members are operatively connected.
